BELT PURSE

Max Tenzer, University City, Mo.

Application March 23, 1950, Serial No. 8,711

Term of patent 14 years

(Cl. D87—3)

To all whom it may concern:

Be it known that I, Max Tenzer, a citizen of the United States, residing at the city of University City, in the county of St. Louis and State of Missouri, have invented a new, original and ornamental Design for a Belt Purse, of which the following is a specification, reference being made to the accompanying drawing, forming part thereof.

In the accompanying drawing:

Figure 1 is a front perspective view of a belt purse, showing my new design.

Figure 2 is a rear perspective view thereof.

The dominant feature of my design for a belt purse, having matching double stitched, spaced apart, vertical seams on the front and back thereof, resides in the pocket located between said seams on the front thereof, the slide fastener

closure of said pocket being set off by double seams and rivets being located at the top and bottom corners and center bottom of said pocket.

I claim:

The ornamental design for a belt purse, as shown and described.

MAX TENZER.
